MOSES G. HUBBARD, OF CHATHAM, NEW JERSEY.

THERMOSTATIC VALVE.

Application filed February 12, 1924. Serial No. 692,222.

This invention relates to thermostatic valves and more particularly to a thermostatic valve adapted for use in steam heating systems in which steam or steam vapor is used. Such systems have radiators, steam pipes, or radiating coils which are filled with steam in order to heat the surrounding air. Steam is supplied from a furnace and the steam may be supplied at any pressure 10 from a mere vapor to quite an appreciable pressure up to the ordinary low pressure limit of 15 pounds per square inch. In many such systems the mode of operation requires that the entire system be open to the atmosphere when it is cold and that the parts which should function as heaters be filled with steam when hot. As the hot and cold conditions frequently follow one another it is necessary to provide some suitable means for the purpose of permitting the air to escape from the system when it is being heated and to permit air to enter into the system when it is cooling off. It is also necessary to seal up the steam filled 20 parts so as to prevent the escape of steam. These devices are known as air valves.

The air valves heretofore constructed and available for use in steam heating systems have not been entirely satisfactory. The 30 valves have been defective in that they are slow and uncertain in operation and in almost every case cause a most annoying noise. They frequently permit the steam to hiss out after the air has been expelled or they 35 permit vapor in the exhaust to condense and be sprayed out onto the walls, floor or furniture. They also permit water to accumulate in the interior and then blow this water out on surrounding furnishings. As 40 this water may be hot, it is more damaging than an equivalent quantity of cold water. They fail to open at the instant a favorable pressure difference exists for air to enter the radiator, but wait for a lowering in temperature. They have required constant adjustment and, as this is generally in the 45 hands of inexperienced persons, ignorant of the construction of the valves, the valves are very often injured or destroyed by this 50 adjustment and can not then function. They deteriorate rapidly and frequent renewal is necessary. The life of air valves heretofore available has been considerably shorter than that of the radiators; and these air valves 55 invariably bring annoyance, trouble, and expense.

An object of the present invention is to provide an improved thermostatic air valve in which a thermostatic member is used for controlling the seating and unseating of a 60 movable member so as to control the flow of fluid past that member.

Another object of the invention is to provide a thermostatic air valve with means to prevent the escape of water in liquid 65 form.

Another object of the invention is to provide a thermostatic air valve for steam heating devices in which all condensate formed inside the valve is drained directly back 70 into the radiator or supply line.

Another object of the invention is to provide an air valve having a closed casing with an inlet for steam and an outlet for condensate, so spaced that water cannot remain 75 inside the casing, and the valve cannot become water logged.

Another object of the present invention is to provide an air valve for steam heating devices in which a member is moved off a 80 seat by the thermostat when the valve is cold, thereby permitting air to pass, and repass, and to arrange the thermostat and member so that when the thermostat is heated, the member may become seated and held in position by the steam pressure to prevent the escape of steam through the valve.

Another object of the invention is to provide a thermostatic air valve having a casing which conforms to the shape of the thermostatic member of non-circular cross section so as to economize space inside the casing.

Another object of the invention is to provide a thermostatic air valve wherein a hollow member acts as a support for the thermostat and movable parts of the valve mechanism and at the same time acts as a vent pipe to permit the flow of air. The 100 invention also contemplates the heating of this pipe so as to reheat the exhaust and cause it to pass out as steam or vapor alone without any condensation.

Another object of the invention is to provide an air valve mechanism having massive parts adapted to be heated to high temperature by the steam so that these parts will be hot enough to eliminate the possibility of the formation of drops of water.

Another object of the invention is to provide an air valve, the interior of which is

maintained full of gas which is at the same pressure as that which exists inside the radiator or steam pipe line with which it is connected.

5 Another object of the invention is to provide a thermostatic air valve in which there is lost motion between the thermostat and the member which closes the valve.

10 Another object of the invention is to provide a thermally controlled valve which is open when below a predetermined temperature and which is closed above a predetermined temperature, the valve being held closed by gravity and the pressure of the 15 fluid present unaffected by any temperature pressure relation which may exist in fluid. I have found such a feature of great value in thermostatic air valves for use in steam heating systems, as the construction of the 20 valve permits its use on steam lines of any pressure. Also there is an entire absence of wear brought about by fluctuation of steam pressure.

25 Another object of the invention is to provide a thermostatic air valve which responds to the slightest vacuum in the radiator, even before there is sufficient change in temperature for the thermostatic member to open the valve.

30 The accompanying drawings show, for the purpose of illustration, several of the many possible embodiments in which my invention may take form.

35 Fig. 1 is an elevational view partly in section of an entire air valve;

Fig. 2 is a section on the line 2—2 of Fig. 1, taken in the direction of the arrows, the parts being in the position assumed when cold;

40 Fig. 3 is a view similar to that of Fig. 2 of the upper part of the apparatus, the parts being heated;

Fig. 4 is a section on the line 4—4 of Fig. 1;

45 Fig. 5 is a section similar to Fig. 2 of a modified form of the invention;

Fig. 6 is a section on the line 6—6 of Fig. 5;

50 Fig. 7 is a section similar to Fig. 2 of another modified form and;

Fig. 8 is a section taken on the line 8—8 of Fig. 7.

Reference is now made to the form of invention illustrated in Figs. 1 to 4, inclusive.

55 A base or attaching member 5 has a screw threaded plug 6, which is adapted to be threaded upon the usual apertured boss provided on radiators for the attachment of air valves. The plug 6 is provided with two horizontal passages 7 and 8. In the drawing the passage 7 is shown directly above the passage 8 and this arrangement is preferred as it economizes space. In this case, the passage 7 is shorter than the passage 8 and it meets a vertical passage 9, which

extends toward the upper surface 10 of the block 5. It is preferably counter-bored at 11 to accommodate a tube 12, which may be soldered in place. The lower hole 8 connects with a second vertical hole 13, which is also carried to the upper surface 10 of the base 5. This hole is here shown as being directly back of the tube 12. The material underneath the outer end of the hole 8 is cut away as indicated at 14 for a purpose to be described.

The member 5 is also provided with vertical drilling 15 which is connected to a hollow supporting member 16 in the form of a tube, soldered in a counter-boring in a manner similar to the fastening in of the tube 12. The tube 16 is much longer than the tube 12. It passes up parallel with this tube and then, in the form shown in the drawing, is bent as at 17 so that the upper end 18 of this tube is in the center of the structure. The tubes may be fastened together by a drop of solder 16', which makes the structure more rigid. The upper end of the tube 16 is suitably fastened, as by soldering, to a member 19 and shelf 20, the upper surface 21 of which may slope as indicated. An aperture 22, preferably a reamed hole, communicates with the interior of tube 16 and the material about the upper edge of this hole then has a suitable configuration so that a seat 23 is formed for a ball 24. A housing 25 is provided about the seat 23 and this housing is covered by a member 26, the housing being open at the lower end 27. The surface 20 may be horizontal and, in that case, I prefer to bring the housing 25 so close to the hole that the ball cannot roll onto the horizontal surface, the ball resting on the edge of the hole 22. The member 19 may conveniently be made from a piece of square brass tubing or a piece of sheet material which is folded to shape, a portion of the material being folded down to provide the shelf 20, which preferably extends the full width of the member 19. This shelf may be soldered to the upper edge of the member 19 and when so fastened it reinforces it. As the tube 16 is soldered to this shelf and to an inside wall 28 of the member 19, it is obvious that the member 19 is supported from the base 5 by means of the tube 16.

To the opposite inside wall 29, of the member 19, there is fastened a thermally responsive device 30—36. This device is in the form of a bi-metallic thermostat, preferably made from metals having as great difference in coefficient of expansion as is available. Galvanized iron or stainless steel and zinc form a suitable combination. A thermostat well suited for the purpose may be made from these metals in the following manner:—A strip of galvanized iron 31 is provided with offset ends forming shoulders

as shown, and a piece of zinc 34 is fitted against this piece of galvanized iron between said shoulders. The upper end of the bimetallic structure 30 thereby formed is riveted or soldered to the member 19, the two pieces of dissimilar metal being fastened together as by rivets one of which is shown at 35. A further thermostatic structure 36 is fastened to the lower end of the first structure 30. The structure 36 is made up similar to the structure 30, but is shown as being a little longer so that the upper end 37 of one of the component metal strips extends up through opening 38 in the member 19. In 15 this thermostatic device 30-36, the two ferrous pieces are thus between the two zinc pieces, and with increase of temperature the two structures 30 and 36 approach one another at their upper ends. Beyond the extension 37 is an extension 40 which reaches 20 through the opening 27 in the housing 25 so as to engage the ball 24 when the thermostat is cold. To prevent corrosion and to preserve an intimate union between the thermostatic elements, I prefer to dip the thermostatic elements in solder. The ball is held in place by the housing and the thermostat.

While the parts 5 and 19 may be given any convenient configuration, I have found it preferable to make them square,—as in a square structure the space can be utilized very economically, especially where a bimetallic thermostat is used. The members 19 and 5 are held in proper relation to one another by the tube 16 and an outside cover member 41 is arranged to slip down over the member 19 and onto the member 5. The cover member is provided with a short slot 42 to accommodate the member 6. This cover member 41 may be conveniently made from a piece of square tubing and an ornamental shape can be given it by slitting the tubing appropriately and bending in the top to form a pyramid 43 as illustrated. The lower end of this outside member may be soldered to the base 5, thereby closing up the device.

Assuming that the device has been suitably connected to a radiator, and that steam is approaching the radiator: The thermally responsive device 30-36 will then be cold and positioned, as shown in Fig. 2 so that the extension 40 holds the ball 24 off the seat 23. The steam cannot enter into the radiator, except as the air in the radiator escapes. The valve being open, the air may escape in the following manner: Through the passage 7, tube 12 into the chamber 44, provided by the casing 41, and out through the tube 16 (which may be said to provide a second chamber) and drilling 15. The parts are all massive and the design is such that this escape of air makes no noise. As the air becomes finally exhausted and steam enters the chamber 44, it warms the lower free end

of the thermostatic member and begins to expand it. This warming is accompanied by condensation of steam inside the chamber 44. The condensate drains down the parts and collects on the floor of the chamber. It 70 then drains down into the passages 13 and 8. The steam slowly displaces the air upward and forces it out through the tube 16. The condensate which drips back into the radiator is directed downward by capillary attraction 75 of the cut 14, so that there is no tendency for it to draw upward into the passage 7. It is therefore impossible for the air valve to become water logged. The pressure of the steam or of a mixture of steam and air in the upper 80 end of the chamber 44 will hold the ball 24 down against the seat and effectively seal the opening, so as to prevent the escape of steam. Some steam may, however, pass by the ball and enter the upper end of the chamber formed by tube 16; but as this tube is inside the chamber 44 and is heated by the steam, it is apparent that the steam passing the ball will not condense. Any steam or mixture of steam and air which can escape 85 from the drilling 15 will be dry and no drops of water can possibly be formed at this point because of the drying action in the tube 16 and because the member 5 is heated both by steam and by the heat conducted from the radiator. This prevents the hissing out of steam or spattering of water which has been generally prevalent in air valves heretofore in use.

Reference is now made to Figs. 5 and 6, 100 which describe a modified form of ball check valve. The lower end of this valve, which is omitted from the drawings, may be identical with the lower end of the valve shown in Figs. 1 to 4, and the same cover member 43 105 may be used. According to the present modification, an upper member 50 is provided, which is, to a considerable extent, similar to the upper member 19 previously described. It may be made by cutting off a section of 110 square brass tubing. The upper edge of two sides of this piece of tubing is cut away to accommodate a member 51. This bridging member 51 is provided with a centrally located aperture 52 and is counter-bored at 53 to receive a tube 54, which may be similar to the tube 16. The tube 54 and bridging member 51 are soldered together and the tube 51 is soldered to the member 50 so that 115 the tube 51 may be supported from the base 5. A thermostatic device 55 similar to the member 30 is carried by the upper member 50, either by soldering or riveting. The upper end of this thermostatic member differs from the upper end of the thermally 120 responsive device 30 in the construction of the valve operating means. In the present case, one of the metallic elements of the thermostatic 125 device 55 is bent over, as at 57, to be parallel to the upper surface of the bridging member 130

51 and to be spaced a considerable distance from it. The other element 58 of the thermostat is doubled upon itself as shown at 59 and is then bent out as at 60 so as to be 5 intermediate the portion 57 and the upper surface of the member 51. The finger 60 is provided with a hole 61 somewhat larger than the ball 62.

10 The operation of the device just described is similar to the operation of the device shown in Figs. 1 to 4. In the present case, the fingers 57 and 60 operate as a housing to keep the ball 62 in place. The lost motion, permitted by making the hole 61 larger 15 than the diameter of the ball 62, permits the proper seating and unseating of the ball and permits the ball to be held seated by the pressure of the steam in the upper chamber 44. The ball is positively actuated both 20 ways. In both forms of the device so far described, the parts may be so arranged that the free end of the thermostat is brought over against the anchored end at the temperature of steam. In such case, further 25 increase in temperature will have no appreciable effect in moving the fingers provided for actuating the ball.

30 The instant that the pressure inside the chamber 44 becomes less than atmospheric pressure, the valve opens. This is on account of the ease of moving the ball relative to the seat and may be brought about by an extremely small difference in pressure. The prompt opening of the valve permits the 35 air to flow in quickly, whereas, in some valves the opening is so delayed, on account of the time lag of the thermostat, that considerable difference in pressure exists; a large quantity of air must rush in, thereby creating considerable noise. In single pipe modulating steam heating systems, the mode of operation requires that, when modulating, the pressure inside the radiator must be atmospheric. It is therefore apparent that the 40 air valve should operate on a minimum pressure difference. I have found my valve admirably suited for this purpose, as proper pressure is maintained in the radiator, it being easy for the condensate to return to the 45 supply pipe without surging.

50 Except for the bi-metallic elements of the thermostat, it is preferable to make the entire device of brass fastened together by soldering. In such case, there is nothing to 55 corrode and the device should last indefinitely. The ball may be of hard brass or bronze of the diameter of about $\frac{1}{16}$ of an inch. There will be no appreciable wear on this ball or its seat as a new surface of the ball is presented each time the device is 60 operated.

65 The device is designed so that the heat of steam at atmospheric pressure is sufficient to flex the thermostat and permit the sealing of the opening, and that further movement

of the thermostat owing to increase in temperature has no effect upon closure member of the valve. The device will operate the same irrespective of the change in temperature which accompanies an increase in pressure. Thus the same device will operate, satisfactorily with a wide range of steam pressures. No wear of the parts is brought about by the movement occasioned by the expansion or contraction of the thermostat, when the temperature varies. This feature is an exceedingly important one in my invention as it gets rid of the wearing of the parts brought about by this cause in the older types of air valves. In the present case, the only effect of change of steam pressure is to press the ball more tightly against its seat; but this induces no wear. The movements of the thermostat brought by variation of the pressure of the steam merely change the spacing between the end of the tip 40 and the ball, without bringing them into contact until the disappearance of the steam.

70 When the steam has been cut off from the radiator, the radiator and the device herein discussed both cool. The cooling of the thermostatic elements causes it to move from the position shown in Fig. 1 to the position shown in Fig. 3 and push the ball off its seat. This opens the passage 16, so as to admit air into the radiator. As the parts past which the air moves are made heavy no noise accompanies this transfer of air.

75 The form of structure illustrated in Figs. 7 and 8 resembles the structures heretofore described; but instead of the ball check valve, I here show a flap check valve having a movable member 65 pivoted at 66 to an upper member 67. The seat 68 for this valve may be fastened to the member 67 by soldering and this seat is provided with a sloping face 69, against which the flap of the check valve is adapted to rest. A suitable aperture 70 is provided for communication with the tube 71. In the present case the upper ends 72 and 73 of the thermostat are so arranged that expansion takes place in the other direction as the valve is to be 80 closed by movement to the left. The upper end 74 of the element 72 is bifurcated as shown in Fig. 8 to engage the outer portions 75 in the movable member 65 to the flap valve.

85 It is obvious that my invention may be embodied in many other forms, which it appears to be unnecessary to illustrate. Instead of check valves of the type here shown, other forms of check valves may be used or 90 I may substitute a slide valve or any other form of valve to accomplish the purpose of shutting off communication in the upper end of the chamber. Instead of the base member 95 being made for a right angle connection 100

as shown in the drawings, it is obvious that it may be made for any other angle, and, in case the valve is to rise straight up from the steam chamber, the air-valve connection can be placed directly underneath and straight passages be used instead of angular ones. In such cases, the drilling 15 would, of course, pass down outside of the threaded plug. By making the entire device of comparatively heavy massive parts, and the air outlet of comparatively large diameter, the device may operate without noise as it is difficult to set up vibrations in such massive parts. A thermostatic member is made quite long and hence it is very sensitive in action. The arrangement of inner and outer chambers provides, as is apparent, a dry pipe through which it is impossible for drops of water to be squirted or sprayed out of the exhaust and into the room.

Bi-metallic thermostats operate best when made flat and, hence, in an air valve using a bi-metallic thermostat, space can be economized by using a square member for the outer casing.

I claim:

1. An air valve for steam heating systems having an apertured seat open at one side to the atmosphere, a freely movable member on the other side adapted to open or to close the aperture, a thermostat for operating the movable member, said movable member moving to open position whenever the atmospheric pressure is greater than the pressure inside the system and movable by gravity when the thermostat is cold.

2. A thermostatic air valve for steam heating systems having a port leading to the atmosphere, and an independent closure member for the port said closure member being movable to open the port whenever the pressure in the system is less than atmospheric and siphon means for draining water from said valve.

3. A thermostatic air valve for steam heating systems having a check valve, a thermostat for holding it open when cold and for permitting it to close by gravity when hot, the valve being held closed when hot by the positive pressure of the steam, the valve opening upon the appearance of a negative pressure irrespective of mechanical pressure by the thermostat from heat-bias.

4. An air valve for steam heating devices having a chamber, a freely movable and gravity operable valve in the chamber, a thermostat in the chamber connected to the valve to operate it, and an exhaust passage connecting the valve to the atmosphere, said passage throughout the greater part of its length having a wall inside the chamber where said wall is subject to the heating medium to dry the outgoing gas, said passage being spaced from a wall of the chamber by

a greater distance than the thickness of the passage wall.

5. An air valve for steam heating devices having a chamber, a gravity operable ball check valve in the upper portion of the chamber, a thermostat in the chamber connected to the valve to operate it, and an exhaust passage leading down from the valve to and through the bottom wall of the casing, said passage being inside the chamber where it is subject to the heating medium to dry the outgoing gas.

6. An air valve for steam heating devices having a chamber, a gravity operable check valve in the chamber, a thermostat in the chamber connected to the valve to operate it to open position when cold and permit it to close when hot, and an exhaust passage connecting the valve to the atmosphere, said passage being inside the chamber where it is subject to the heating medium to dry the outgoing gas.

7. An air valve having a base member provided with a threaded plug, a plurality of passages extending through the plug and passing upwardly, one being extended beyond the other whereby said other passage may drain liquid condensed above the base member, the lower end of said last mentioned passage being cut back to drain the water away from the first passage.

8. An air valve having a base member provided with a threaded plug, a plurality of passages extending through the plug and passing upwardly, one being extended beyond the other whereby said other passage may drain liquid condensed above the base member, an additional passage through the base member which communicates with the atmosphere, and a thermostatically operated valve at the upper end of said additional passage.

9. An air valve for steam heating systems comprising a chamber having a ball seat communicating with the atmosphere, a ball freely resting upon said seat, means for connecting said system with the heating chamber and means for discharging water from said chamber into said heating system, the parts being so arranged that negative pressure in the system unseats the ball.

10. An air valve for steam heating systems comprising a chamber having a ball seat communicating with the atmosphere, a ball freely resting upon said seat, and a thermostat adjacent to said ball and arranged to bear laterally thereon to unseat the ball when the thermostat is cold.

11. An air valve for heating systems having two chambers, one communicating directly with the system and the other to the atmosphere, a ball valve seat affording communications between said chambers and a ball freely resting upon said seat to control

the communication between the chambers, said valve opening when the pressure in the second chamber exceeds the pressure in the first, and siphon means for withdrawing water from said first mentioned chamber.

12. An air valve for heating systems having two chambers, one communicating directly with the system and the other to the atmosphere, a ball valve seat affording communications between said chambers and a ball freely resting upon said seat to control the communication between the chambers, said valve opening when the pressure in the second chamber exceeds the pressure in the first, and siphon means for withdrawing water from said first mentioned chamber, and a thermostat within said first mentioned chamber adapted to bear laterally upon said ball when said thermostat is cold, to unseat the same.

13. An air valve having a base member for attachment to a radiator, a thermostat, a hollow support for the thermostat, the support being open at the top, a cover, a passage connecting the hollow support to the atmosphere other than through the space

between said hollow support and cover, and means under the control of the thermostat for closing the upper end of the support, said means including a valve member having a field of operation exterior to the hollow support.

14. A thermostatic air valve having a chamber, a thermostat, a ball check valve which is closed when the thermostat is hot, and an exhaust pipe inside the chamber connected to the check valve, the heating medium in the chamber heating the pipe to dry the contents thereof.

15. A thermostatic air valve having a chamber, a thermostat movable laterally therein, a ball check valve which is closed by gravity when the thermostat is hot and opened by actuation of the thermostat when cold, an exhaust pipe inside the chamber connected to the check valve, and so located and constructed that steam in the chamber constitutes a heating means or medium in the chamber, for heating the pipe to dry the contents thereof.

MOSES G. HUBBARD.
